UNITED STATES PATENT OFFICE.

THEODORE T. WEBER, OF COLUMBUS, OHIO, ASSIGNOR TO THE OHIO GAS GENERATOR & MANUFACTURING COMPANY, OF COLUMBUS, OHIO, A CORPORATION OF OHIO.

GAS-GENERATOR.

1,222,167.

Specification of Letters Patent. Patented Apr. 10, 1917.

Application filed July 20, 1914. Serial No. 851,847.

To all whom it may concern:

Be it known that I, THEODORE T. WEBER, a citizen of the United States, residing at Columbus, in the county of Franklin and State of Ohio, have invented certain new and useful Improvements in Gas-Generators, of which the following is a specification.

My invention relates to gas generators and refers particularly to a generator for producing gas from kerosene or some similar comparatively heavy hydro-carbon.

Various attempts have been made to use kerosene in connection with internal combustion engines of motor vehicles and the main object of my invention resides in so constructing my generator; that it is particularly adaptable for this use. In this connection it is also my object to produce a generator which will be small and compact in size but very efficient and at the same time have a large capacity for the generation of the explosive gas.

In attaining these objects, my generator preferably takes the form of a series of hollow concentric members arranged one within the other and all in communication with each other, certain of these members forming a chamber adapted to contain the hydro-carbon and be heated. The purpose of the remaining concentric members which are all in communication with each other, is to produce a comparatively great heating surface to effect the volatilization by its passage there around to an outlet opening.

The preferred embodiment of my invention is shown in the accompanying drawings, in which similar characters of reference designate corresponding parts, and in which:

Figure 1 is a central vertical section of one form of generator,

Fig. 2 is a section taken on line 2—2 of Fig. 1,

Fig. 3 is a central vertical section of a slightly modified form of generator, and,

Fig. 4 is a section taken on line 4—4 of Fig. 3.

In both types of generators shown, I have provided a main central pipe section 1 forming the basic member of my generator. In Fig. 1 the ends of this pipe are shown as open, while the generator shown in Fig. 3 has the ends closed as at 1^a and 1^b, the cap 55 1^b being suitably formed to permit the pas-

sage of electric wires 1^c and 1^d therethrough, which wires are connected with an electric heating unit 1. In both types of generators shown, the section 1 is suitably threaded to receive pairs of end plates 2, 3 and 4, each set of end plates being securely fastened to concentrically arranged pipe sections 5, 6 and 7 respectively. These pipe sections gradually increase in size and are adapted to lie within the other as is shown. In Fig. 1, the pipe 1 is adapted to be connected to any type of heating means, such as with the exhaust pipe from an internal combustion engine. In this manner, the pipe 1 becomes very warm and the space between this pipe section and the section 5 is adapted to be partially filled with some hydro-carbon, preferably kerosene. This kerosene is fed to this chamber by means of a pipe 8 provided along its lower edge with a suitable number of apertures 9 and being itself fed from a central upwardly extending pipe section 10. This latter pipe section leads into a four-way fitting 11 located in the upper portion of the pipe section 7 and then is turned at a right angle and connects with any suitable type of supply pipe 12. The four-way fitting 11 is so formed to present a comparatively large opening 13 into the chamber formed by the pipe sections 6 and 7, this opening being considerably bigger than the external diameter of the pipe section 10. The remaining two outlet portions 14 and 15 of this fitting, are adapted to supply the correct amount of air to the generated gases and lead to a suitable point of consumption respectively.

I have found that to break up the kerosene by the use of an intense heat, it is absolutely essential that a sufficient amount of air or oxygen be supplied to effect the oxidation. I have, therefore, provided two short pipe sections 16 securely threaded into each of the members 5, 6 and 7 and open at their lower and upper ends to supply the correct amount of air to the chamber formed by the sections 1 and 5, or the chamber in which the gases are generated by the applied heat. The amount of opening of the upper end of these pipe sections 16 may be regulated by any suitable type of fitting such as is shown at 17 wherein its upper end 18 is of a comparatively less diameter than the end attached to the pipe section itself.

In order that the generated gases may be

heated for some considerable time and also be maintained in a warm condition during their outward passage, I have provided each of the pipe sections 5 and 6 with outlet 5 openings 19 and 20, these openings in the succeeding pipe sections being disposed at diametrically opposite points to insure the complete circulation of the gases around at least half the space formed between these 10 two sections, and the opening 20 being disposed at a point diametrically opposite the outlet opening 13 formed in the fitting 11.

In Fig. 3, where the electric heating unit is used, I have provided the section 1 with 15 outlet openings 1^f to permit the passage of the generated gases into the chamber formed between the sections 1 and 5 and thereafter, the outward passage of these gases is the same as in the structure shown in Fig. 1. 20 All the fittings used in connection with the structure shown in Fig. 3, are similar to that used in the structure shown in Fig. 1, with the exception that the inlet pipe 10 leads directly into the pipe section 1 as is 25 shown at 1^g as opposed to the feed arrangement shown at 8.

In order to remove any residue which may collect in the generator, I have provided its lower portion with a drain pipe 21 leading 30 down into a fitting 22 and then turned at right angles and into an outlet pipe 23. This fitting 22 is also provided with an enlarged portion 24 forming an opening into the chamber formed between the lower portion 35 of the members 6 and 7, while at the point opposite the outlet pipe 23 this fitting has attached thereto a check valve 25. This check valve is provided to relieve any excess pressure within the generator itself 40 should this pressure become excessive.

From the above description, it is believed

the operation of my generator will be clearly understood. Kerosene is supplied to the innermost chamber and this chamber heated in any desired manner either by the use of 45 an electric heating unit, exhaust gases, etc. Air is then also supplied to this innermost chamber by the pipe sections 16 and this supply of air, together with the heat, causes the volatilization of the kerosene 50 itself. The true action is that the kerosene is broken up into a number of gases lighter in molecular weight than the true composition of kerosene and these gases are then maintained in a warm condition and are allowed to circulate around the various pipe sections to the outlet portion 15. In order 55 to form an explosive mixture out of these gases, an additional amount of air is supplied through the opening 14 before its 60 passage out through the opening 15.

What I claim, is:

A gas generator comprising a central pipe, a plurality of end plates of different diameters on opposite ends of said pipe, a 65 plurality of cylinders of different diameters connecting said end plates to form a plurality of chambers, a connection for feeding hydrocarbon to the innermost chamber formed, a connection for also supplying air 70 to said chamber, said innermost chamber being adapted to be heated, and connections for withdrawing the gas after circulating it around the remainder of the chambers and mixing an additional supply of air there- 75 with.

In testimony whereof I affix my signature in presence of two witnesses.

THEODORE T. WEBER.
